UNITED STATES PATENT OFFICE

FRANK E. LEAHY, OF PITTSBURGH, PENNSYLVANIA, ASSIGNOR TO REPUBLIC FLOW METERS CO., OF CHICAGO, ILLINOIS, A CORPORATION OF ILLINOIS

DIFFERENTIAL COMPENSATING FLOAT

Application filed July 2, 1926. Serial No. 120,113.

This invention relates to a float arranged to be actuated by differential gas pressure and has for its object the provision for such a float in which the movement may be damped and in which the amount of damping may be 5 regulated and may be made different for movements of the float in different directions.

The invention is exemplified in the combination and arrangement of parts shown in 10 the accompanying drawing and described in the following specification and it is more particularly pointed out in the appended claims.

In the drawing, the figure is a diagrammatic vertical, sectional view showing one 15 embodiment of the invention as applied to a gas producer furnace. It will be understood that the illustration is given by way of example and that the float is applicable to many purposes other than that of regulating 20 a gas producer, and that the construction of the float itself may be varied without departing from the spirit and scope of the invention.

In the drawing, the numeral 10 designates 25 a gas producer having a blower 11 to which steam is supplied by means of a steam line 12. The blower 11 is of the injector type by means of which a jet of steam aspirates the air and furnishes a mixture of steam and air 30 to the producer chamber. Instead of a steam aspirator, a turbo blower may be used as is done in many cases in connection with gas producers. With either form of blower, the amount of gas produced is a direct function of 35 the air supplied and consequently of the steam supplied through the pipe 12. The gas is discharged from the producer 10 through a gas main 13 in which it is desirable to maintain a constant gas pressure. To 40 accomplish this result, a pipe 14 communicates with the interior of the main 13 and has its opposite end 15 opening within a bell float 16 which is inverted in a body of liquid 17 contained in a vessel 18. The float 16 is 45 connected by a link 19 with a lever arm 20 which operates a valve 21 to control the steam supply to the pipe 12. The valve 21 is a balanced steam valve to permit ready response to the force exerted by the float 16. 50 It will be seen that when the pressure de-

creases in the main 13, the float 16 will sink and tend to open the valve 21 to supply more steam to the producer, thus causing more rapid production of gas and a consequent rise in pressure in the main. If the pressure becomes excessive in the main 13, the float 16 will be raised tending to close the valve 21, thus decreasing the supply of steam and reducing the rate of production and consequently the pressure in the main 13. It has 55 been found that where a bell float is provided with straight sides, the response to changes in pressure in the main 13 is so rapid that extreme variation in the steam flow is produced which give rise to faulty operation 60 of the producer. In many cases, the amount of steam admitted incident to a drop in pressure is in excess of that required to restore the pressure so that the pressure is raised above 65 normal and the float goes to the opposite extreme giving rise to a "hunting" operation of the float. To overcome these difficulties, the float 16 is provided with an internal chamber 22 formed by an inclined annular wall 23 and an annular bottom 24. Communication 70 between the chamber 22 and the chamber 17 is provided by restricted openings 25 which may be in the form of perforations through the bottom 24, as shown in the drawing, or 75 may be in the form of a slit in the side of the wall 23, or any other suitable form. With 80 this arrangement, it will be seen that with any variation of the gas pressure, the body of liquid within the float will resist movement of the float until the liquid passes through the openings 25 to equalize the liquid level in the chambers 17 and 22. This prevents 85 sudden changes in the steam flow, gives more uniform operation of the producer and avoids "hunting" of the float. 90

In the drawing, the wall 23 is shown as inclined outwardly toward its upper edge. With this arrangement, a less quantity of liquid passing through the perforations 25 will restore the liquid level when the float is 95 depressed than is required when the float rises. This will permit quicker response to a decrease in the gas pressure than is permitted for an increase in the pressure. It will be apparent that the difference between 100

the quickness of the response for up and down movement of the bell may be regulated by changing the angle of the wall 23 and the condition may be reversed by inclining the 5 wall inwardly instead of outwardly toward its upper edge, the amount of movement of the valve 21 for a given variation in gas pressure may be adjusted by changing the length of the lever arm 20. The damping effect may 10 be regulated by regulating the size of the perforations 25.

In addition to the float 16, a second float 26 supported on liquid 27 in a vessel 28, similar to the support for the float 16, may be 15 provided. The pipe 29 is connected with the pipe 14 and opens beneath the float 26. The float 26 is provided with a damping chamber 30 similar to the damping chamber 22 but the wall of the chamber 30 may be 20 straight instead of inclined to give equal sensitiveness in both directions. The float 26 is connected to a pivoted pointer 31 which travels along a scale 32 and may be provided with a weight or other arrangement 33 for 25 tending to hold the pointer in a zero position. By this means, a pressure gage is provided which will indicate the pressure in the main 13.

I claim:—

- 30 1. A pressure responsive device of the class described comprising a receptacle for a liquid, a partly submerged inverted bell-shaped member adapted to move up and down in said receptacle, said bell-shaped member having 35 an imperforate top and side walls and an extension on said walls extending inwardly and then upwardly therefrom, the submerged portion of the bell-shaped member having openings therethrough and said upwardly 40 extending portion being shaped so that the cross-sectional area of the space enclosed thereby varies from the lowermost part of said enclosed space to the top of said enclosed space, the upper edge of said upwardly extending portion terminating above the liquid 45 level in said receptacle to prevent any liquid from flowing between said receptacle and said bell-shaped member except through said openings.
- 50 2. A pressure responsive device of the class described comprising a receptacle for a liquid, a partly submerged inverted bell-shaped member adapted to move up and down in said receptacle, said bell-shaped member having 55 an imperforate top and side walls and an extension on said walls extending inwardly and then upwardly therefrom, the submerged portion of the bell-shaped member having openings therethrough and said upwardly 60 extending portion being shaped so that the cross-sectional area of the space enclosed thereby increases from the lowermost part of said enclosed space to the top of said enclosed space, the upper edge of said upwardly extending portion terminating above the liq- 65 uid

uid level in said receptacle to prevent any liquid from flowing between said receptacle and said bell-shaped member except through said openings.

3. A device as claimed in claim 1, in which the bell-shaped member is so constructed that less movement thereof is required to bring the liquid to the desired level when the bell-shaped member is at the lowermost portion of its travel than when it is at its uppermost portion. 70

4. A pressure responsive device of the class described comprising a receptacle for a liquid, a partly submerged bell-shaped member adapted to move up and down in said receptacle, said bell-shaped member having an imperforate top and parallel side walls and an extension on said walls extending inwardly and then upwardly therefrom, the submerged portion of the bell-shaped member having openings therethrough and the upper edge of said upwardly extending portion terminating above the liquid level in said receptacle to prevent any liquid from flowing between said receptacle and said bell-shaped member except through said openings. 80

In testimony whereof I have signed my name to this specification on this 21st day of June, A. D. 1926.
